AUGUSTIN AUGUSTIN-NORMAND, OF LE HAVRE, FRANCE, ASSIGNOR TO CHANTIERS ET ATELIERS AUGUSTIN-NORMAND, OF LE HAVRE, FRANCE, A CORPORATION OF FRANCE.

PNEUMATIC EVACUATING DEVICE FOR COMPRESSORS.

1,402,707.

Specification of Letters Patent.

Patented Jan. 3, 1922.

Application filed April 13, 1920. Serial No. 373,583.

To all whom it may concern:

Be it known that I, AUGUSTIN AUGUSTIN-NORMAND, engineer, citizen of the French Republic, residing at Le Havre, Department of Seine-Inférieure, in France, and having P. O. address 67 Rue du Perrey, in the said city, have invented certain new and useful Improvements in Pneumatic Evacuating Devices for Compressors; and I do hereby declare the following to be a full, clear, and exact description of the invention, such as will enable others skilled in the art to which it appertains to make and use the same.

This invention relates to an automatic 15 evacuating device for air compressors and other apparatus for the purpose of avoiding the explosions which are often produced at starting and stopping, when the pressure in the compression chambers of said compressor becomes higher than the operating 20 pressure and a high temperature is produced in such apparatus.

The object of the present invention is to provide the compressor with special blow-off valves and controlling means therefor, 25 said valves opening outwardly and acting automatically each time the compressor is started or stopped, and which, in addition, blow off each time the pressure becomes too 30 great in the compression chamber, irrespective of the pressure of the air in the air reservoirs, which automatic operation of 35 said device being controlled by the starting and stopping lever of the engine, (not shown), operating the compressor.

At stopping, the back leakage from the air reservoirs and from the higher stages towards the lower stages by reason of valves which do not fit tightly, or past the piston 40 segments, becomes more important and if the run has been of long duration a certain quantity of the lubricating oil may find its way into the compression chambers of the compressor. As this oil has rarely a sufficiently high flash point, the mixture of its 45 vapour and compressed air which may have a higher ratio than the designed ratio can ignite spontaneously during the last turns of the machine which precede the stop. At 50 the moment of starting, which follows a stop during which leakages have had time to produce their full effect and during which the high temperature of the walls has volatilized a part of the oily layer which covers 55 them, the same accident may occur. On the

other hand, during normal operation it is rare that the combined influences of the disturbing factors above mentioned are sufficiently accentuated to produce other than partial combustions without a dangerous 60 rise of pressure and of which the effect is simply to foul the delivery valves if there is an excessive supply of lubricant.

It will be clear therefore that it will be necessary to expel the air charges from all 65 the compression chambers of a compressor at the moment of stopping and during starting to avoid a dangerous operation.

According to the present invention supplemental cams are mounted on the axle of 70 the lever which operates for example the eccentric shaft on which are pivoted the needle levers and starting levers of a Diesel engine (not shown) driving a compressor A. When this lever is brought into the position 75 which corresponds to starting and stopping of the engine, one of the said cams comes into action and presses upon a rod which opens a distributing valve for compressed air in a pipe which transmits pressure to all 80 the evacuating valves of the compressor. The closing rod of each of these valves is then raised by the action of compressed air under a differential piston and evacuation 85 is effected.

The accompanying drawing shows in perspective a portion of the engine starting lever and the transmitting apparatus automatically controlled thereby which in the example shown is pneumatic, and in elevation 90 a two-stage compressor A furnished with two evacuating valves B and C.

The starting lever 1 is fixed on a shaft 2 on which is secured in addition to the engine control, (not shown) a cam 3 called 95 the evacuating cam, this cam having two projections 4 and 5 suitably spaced apart so as to act on the control rod 6 of a valve 7 mounted inside a distribution box 8. The valve 7 is adapted to connect an inlet pipe 100 9 for compressed air, which, for example, may be supplied from the starting reservoirs (not shown), through the passage 10 in which the valve 7 is mounted, with a conduit 11 which communicates with a passage 105 12 in the box 8.

A valve 13 arranged in the passage 12 is mounted on a rod 14 on which a cam 15 carried by the shaft 2 is designed to operate. The passage 12 can be put into connection

with the external air through a port 16. Springs suitably arranged constantly maintain the valves on their seats when not opposed by the action of the cams on the valve rods. The conduit 11 of the distribution box is prolonged on the other side of the passage 12 by a port 11' connected by a tube 17 with the evacuating valves of the compressor.

10 These valves are constituted by a pointed rod 18 controlling communication between an atmospheric port 20 and a passage 19 connected with the compressor. The valve rod 18 is fixed on a little piston 21 subjected to 15 the action of a spring 22 and able to move in a suitable housing or cylinder. A passage 23 opening into the lower part of the cylinder of the piston 21 connects the cylinder with the pipe 17 supplying compressed air.

20 The operation of the arrangement is as follows:

When the engine governing lever 1 is in the vertical position marked "Petrol", the cam 3 is inoperative. As soon as the lever is lowered in the direction of the position marked "Stop", the cam 5 comes into operation and presses on the rod 6 which opens the valve 7 of the compressed air distributor and air pressure is thereby transmitted to 30 all the evacuating valves of the compressor. The rod 18 of each of these valves is raised by the action of the compressed air under the differential piston and evacuation is effected.

35 At the position "Stop" evacuation ceases. When the lever is moved below this position evacuation is resumed and continues when the lever is in the lower position marked "Air" when the engine is started.

40 It only ceases when the lever is raised and attains the position of normal operation marked "Petrol". At this moment the cam 15 operates the valve 13 for emptying the piping located between the distribution box 45 and the evacuating valve. The cylinders of all the evacuating valves are thereupon connected to the atmosphere and the compressor can at once begin to operate.

The position of the lever shown in the 50 figure is that of starting on compressed air. It will be seen that the projection 4 of the cam 3 presses on rod 6 and holds the valve 7 open whereupon the passage of air in the direction of the arrows raises all the pistons 55 21 and evacuates the compressors by the ports 20.

At the "Stop" position the rod 6 will be in the hollow between the two projections 4 and 5 and closes the communication between pipe 60 9 and pipe 17. The object of this is to prevent the pistons 21 which are not statically packed from being exposed to the pressure of the starting reservoirs during the whole period of a stop.

65 At the "Petrol" position the other pro-

jection 5 of the cam 3 passes the rod 6 which is free to rise, on the other hand, the projection of the cam 15 presses on the rod 14 and operates the valve 13 so that the pipe 17 will be connected to the atmosphere by the 70 port 16 whilst the valve 7 forms a stop valve for the pipe 9.

It is clear that various other means of transmission could be employed, mechanical, hydraulic, or electrical, for example. 75

The arrangements can also be adapted to any other motor control, whether this be thermal or electrical.

The evacuating valves act at the same time as safety valves, being forced from the outside towards the inside by a spring the pressure of which slightly exceeds the normal pressure. It may be observed that their presence is always useful and that they do not duplicate the safety valves with which 80 air coolers are furnished. In fact, these latter are separated from the compression chambers in the first place by piping which permits losses of charge and in the second place by delivery valves which may by reason of mechanical damage remain wedged 85 in the closed position and so interrupt all communication.

It is to be understood that the compressed air admitted through the device when the 90 valve 7 is open by the cams 4 and 5, has nothing to do with supplying the compressed air for starting or operating the compressor A, but is only used to lift the members 18 of the evacuating valves B and C so that 100 the compressor may be evacuated through the passages 19 and 20 of each of the valves B and C, the devices being used in conjunction with a two stage compressor.

Having now particularly described and 105 ascertained the nature of my said invention and in what manner the same is to be performed, I declare that what I claim is:—

1. In an evacuating arrangement for air compressors or the like, the combination 110 with a control lever of evacuating valves associated with said compressor, compressed air supply and exhaust valves for operating the evacuating valves, means for establishing communication between said air supply 115 and exhaust valves and evacuating valves and means carried by said control lever automatically operating the air supply and exhaust valves for opening said evacuating valves at the proper time and for the purpose specified.

2. In an evacuating arrangement for air compressors or the like, the combination with a control lever of a shaft for said lever, 125 evacuating valves associated with said compressor, compressed air supply and exhaust valves for operating the evacuating valves, means for establishing communication between said air supply and exhaust valve and evacuating valves, and cams carried by the 130

shaft of said control lever for operating the air supply and exhaust valves for opening and permitting the closing of the evacuating valves at the proper time and for the 5 purpose specified.

3. In an evacuating arrangement for air compressors or the like, the combination of a control lever, a shaft for said lever, evacuating valves associated with the compressor, 10 compressed air supply and exhaust valves for operating the evacuating valves, a pipe for establishing communication between said air supply and exhaust valves and evacuating valves and a pair of cams carried by the 15 shaft of said control lever, one of said cams adapted to operate the compressed air supply valve for opening the evacuating valves, and the other cam adapted to operate the exhaust valve at the desired time for exhausting 20 to the atmosphere the pipe supplying the compressed air to the evacuating valves.

4. In an evacuating arrangement for air compressors or the like, the combination of

a control lever, a shaft for said lever, evacuating spring pressed piston valves associated with the compressor, compressed air supply and exhaust valves for operating the evacuating valves, a pipe for establishing communication between said air supply and exhaust valves and evacuating valves and a pair of cams carried by the shaft of said control lever, one of said cams adapted to operate the compressed air supply valve for opening the evacuating valves, and the other cam adapted to operate the exhaust valve at the desired time for exhausting to the atmosphere the pipes supplying the compressed air to the evacuating valves, permitting the 25 springs to close the evacuating valves. 30 35

In testimony whereof I affix my signature, 40 in presence of two witnesses.

A. AUGUSTIN-NORMAND.
